UNITED STATES PATENT OFFICE.

ANTONIO C. PESSANO, OF PHILADELPHIA, PENNSYLVANIA, ASSIGNOR TO
THE GEORGE V. CRESSON COMPANY, OF SAME PLACE.

DESIGN FOR A JOURNAL-BOX.

SPECIFICATION forming part of Design No. 32,588, dated April 24, 1900.

Application filed March 19, 1900. Serial No. 9,335. Term of patent 14 years.

To all whom it may concern:

Be it known that I, ANTONIO C. PESSANO, of the city and county of Philadelphia, in the State of Pennsylvania, have invented a new 5 and original Design for Journal-Boxes, of which the following is a specification.

My design for journal-boxes is shown in the accompanying drawings, in which—

Figure 1 is a plan view of a journal-box embodying the design. Fig. 2 is a side elevation of the same, and Fig. 3 is an end view.

The journal-box consists of an approximately-cylindrical hollow box having a longitudinal cylindrical opening E extending 5 from end to end.

A is the lower half of the box, and B F the upper portion. The lower portion A tapers toward the ends and at one end has a slightly-enlarged transverse ridge h. The upper portion B F terminates at the edges in flanges b, which extend along the upper edge of the lower portion A. The part B of the upper portion is of slightly-smaller diameter than the part A and has two transverse ridges C C, 5 formed with central bosses c, and a central

recessed boss d between the ridges C C. The end part F of the upper portion has at its end a somewhat-enlarged transverse rib f, which forms a continuation of ridge h of the lower portion A. The lower portion A has at the 30 middle of the upper edge on each side a lug or projection a.

The essential features of the design consist of the approximately-cylindrical hollow box having the lower portion A tapering toward 35 the ends, and having the ridge h, adjacent to one end, and the upper portion B F, formed with the transverse ridges C C and f.

What I claim as new, and desire to secure by Letters Patent, is as follows: 40

The design for a journal-box substantially as described and as shown in the accompanying drawings.

In testimony of which invention I have hereunto set my hand.

ANTONIO C. PESSANO.
